SHOULDER PAD

Jacob L. Kleinman, New York, N. Y.

Application January 18, 1947, Serial No. 722,868

12 Claims. (Cl. 2—268)

1 This invention relates to shoulder-pad construction and more particularly to a type of shoulder-pad that is provided with means adapted to hold such shoulder-pad in desired position without the aid of pins or without the aid of sewing, and wherein such shoulder-pad may be removed without resorting to undoing of seams or of sewing.

My novel shoulder-pad construction is capable of being used in connection with various styles or types of garments which are provided with shoulder straps, but particularly with the type, for example, forming brassières, slips, underwaists, undergarments, corset covers, or any combination of the aforementioned garments.

In accordance with my invention, I produce a shoulder-pad provided with a pair of separable jaw portions adapted to support a shoulder strap therebetween, in a manner whereby such shoulder-pad may be held in desired position upon the wearer's shoulder, and wherein the underlying jaw portion may be adapted to act as a cushioning means for such shoulder strap thereby eliminating shoulder-strap irritation to the wearer's shoulder, and wherein the jaw portions may be separated from each other and be removed from such shoulder strap thereby removing the shoulder-pad from the wearer's shoulder.

There is, therefore, thus produced, in accordance with my invention, a shoulder-pad, capable of being held in desired position upon the wearer's shoulder, for various desirable purposes, without the aid of pins or that of sewing, and to be removed therefrom without the undoing of seams, thereby eliminating the annoyance and hazardous effects of sewing or undoing of seams.

To illustrate the ordinary commercial utility of my novel shoulder-pad in daily life, a shoulder-pad constructed in accordance with my invention, of whatever style or type it may be made, could be utilized to great advantage; the fact that a shoulder-pad could be placed upon the wearer's shoulder, for the purpose of raising the garment shoulder to a higher point, without the annoyance of trying to attach such shoulder-pad to the under-face of the garment shoulder, particularly without resorting to the necessity of sewing, a matter which is a difficult task to most people, especially to those not trained in the sewing profession, would render great comfort and satisfaction to the wearer.

Particularly would such be the case with the shoulder-pad if made in accordance with my invention. It is a known fact that shoulder straps of brassières, slips, or similar under-garments,

2 usually press tightly upon the wearer's shoulders, often cut quite deeply into the shoulder flesh, leaving unsightly marks which are objectionable and irritable, often times even painful, to the wearer. But applicant's shoulder-pad would eliminate the above-mentioned objectionable features; the underlying portion of applicant's shoulder-pad would act as a cushioning means keeping such shoulder straps away from direct contact with the wearer's shoulder skin, thereby preventing the possibilities of causing discomfort to the wearer, and instead providing comfort, ease and satisfaction to such wearer to an extent whereby such shoulder-pads would become an indispensable wardrobe item, and thus quite valuable to the trade commercially.

Furthermore, such a shoulder-pad, if constructed in accordance with my invention, may also act as an under-arm shield carrier, and may be provided with locking means adapted to hold such shield in desired position. The fact that the shield, carried by applicant's shoulder-pad, hangs independently under the wearer's arm and does not have to be sewn on to the garment's armhole, makes it possible for such shield to be used in connection with various garments that the wearer may use, thereby eliminating the necessity of buying a separate pair of dress-shields for each one of the wearer's garments.

Thus a shoulder pad made in accordance with my invention may be worn with great comfort, as it can be easily used to suit the wearer's requirements at various occasions. It is believed that such shoulder-pad will prove quite valuable commercially.

It may further be stated, that applicant's shoulder-pad may also be used as a buckle-pad if so desired. It is a known fact that buckles used on shoulder-straps of a brassière for the purpose of adjusting the length of such straps cause trouble and discomfort to the wearer. For example, plastic buckles usually break and are therefore not safe for practical use; neither are metallic buckles safe for use from a practical point of view, they usually rust, particularly so when the plating is worn off; the wearer must therefore frequently resort to newly bought buckles, a matter which is quite costly and causes mental irritation and disturbance.

But applicant's buckle-pad eliminates completely the above-mentioned objectionable features and makes the use of the metallic buckle perfectly safe. This accomplishment is possible by reason of having the underportion of the pad positioned under the buckle thereby preventing

the direct contact between such buckle and the skin of the wearer's shoulder. In addition thereto, such underportion also acts as a cushioning means for the buckle thereby preventing the possibility of such buckle scratching or irritating the wearer's shoulder skin. Thus, applicant's buckle-pad may prove to be a very desirable wardrobe item, and quite valuable to the trade commercially.

The variety of possible applications of my novel construction in connection with different articles of apparel, as hereinabove indicated, is so prolific that for the purpose of illustrating the invention the specific embodiment of my invention in its application to a garment exhibiting the greatest difficulties has been selected. Such a garment is one which necessarily must conform most rigidly to the body contours and one which has the field of greatest possible commercial use. For this purpose I have selected for illustration of my novel construction, a garment constituting a brassière provided with shoulder straps adapted to support a shoulder-pad made in accordance with my invention, so that the principles of construction may be best illustrated in the combination of a shoulder-pad together with a shoulder strap of a brassière garment.

The objects of the present invention are attained by a novel construction which will be hereinafter described and illustrated in the drawing in connection with a specific embodiment of the invention.

In the accompanying drawing in which such specific embodiment of my invention is illustrated,

Fig. 1 is a top view of a shoulder-pad in the construction of which my invention has been embodied, showing the position of the shoulder-strap when housed between the jaw portions of the shoulder-pad.

Fig. 2 is a cross-sectional view taken on line 2—2 of Fig. 1, showing the jaw portions in an open position and also in a closed position, (as indicated by the dotted lines) and also showing the shoulder-strap held between the two jaw portions of the shoulder pad when they are in a locked position.

Fig. 3 is a cross-sectional view taken on line 3—3 of Fig. 1, showing the jaw portions and the interlocking means in an unlocked or open position and also showing the manner in which the shoulder-strap is supported by the fastening elements.

Fig. 4 is a perspective view of the shoulder-pad and of the under-arm shield, showing one of the jaw-portions in an open position and the other jaw-portion underlying the brassière shoulder-strap, including the buckle, and also underlying the shoulder-strap of the under-arm shield.

Fig. 5 is a perspective view showing how the shoulder-strap is wound around the buckle for length adjustment and how the buckle is held in desired position, and

Fig. 6 is a perspective view showing that the upper jaw-portion may be made of a lesser thickness than that of the underlying jaw-portion.

Referring more particularly to the drawings, in which similar reference characters identify similar parts in the several views, in my novel shoulder-pad:

Numeral 5 indicates the body of a shoulder-pad having a thickened end portion 6 and thinner side portions 7. The rear portion 8 is divided into two separable jaw-portions or flaps 11

and 12 formed in a manner providing a spaced section 14 between them; the inner faces of the flaps or jaw-portions 11 and 12 are each provided with snap fasteners 15 and 16 for a purpose which will be hereinafter explained.

For the purpose of explaining the features of this invention it may be stated that shoulder-pads are being used for the purpose of raising the shoulder of the wearer's garment to a higher level, and for that reason garments are usually provided with what is known as padded shoulders, such padded shoulders can be made only in heavier built garments, top coats for example. But ladies' wear, particularly blouses, dresses or similar garments, cannot be provided with such padded shoulders. It therefore became a custom that the individual buys covered-shoulder-pads for the purpose of having them sewn on to the inner face of the garment shoulder, but the average person, particularly the one not trained in the sewing profession, usually is at a loss in the art of sewing, and the shoulder-pads therefore do not perform the desired function. Various attempts have been made to eliminate the necessity of sewing the shoulder-pads on to the inner face of the garment shoulder, some have suggested that the shoulder-pads be secured to the garments by means of pins, others have suggested to sew on snap fasteners to the under-face of the garment shoulder and also to the shoulder-pad, but neither of these suggestions are practical. The fault of such suggestions lies in the fact that pins usually rub and irritate the wearer's shoulder, often times injuring such shoulder, or tearing and ruining the wearing apparel which is located under such "pad-and-pins" arrangement; such arrangements are therefore found to be very unsatisfactory to the wearer.

40 The same is true with respect to the snap fastener suggestion; first of all, snap fasteners must be obtained in regular sets, otherwise they will not match with each other and will not have the desired frictional engagement for interlocking purposes, and will therefore not be able to hold the shoulder-pad in desired position. Then again, it is actually impossible to arrange the space between each of the snap fasteners which may be positioned on the inner face of each garment-shoulder to match exactly with the space between each of the snap fasteners that may be positioned on the shoulder-pad. It is therefore quite obvious that the application of a shoulder-pad to a garment shoulder by means of pins, or snap fasteners, is not practical and will only serve to distort the neat appearance of the garment. It will therefore be seen that resorting to the above methods for the purpose of securing a shoulder pad to the desired position on the wearer's shoulder is not at all advisable.

For the above reasons it will be seen that a shoulder-pad, constructed in accordance with applicant's invention, eliminates completely the necessity of resorting to the aid of pins or to that of sewing for the purpose of securing the shoulder-pad to its proper position upon the wearer's shoulder. Applicant's invention teaches an entirely new principle in the application of shoulder-pads to the wearer's shoulder. Applicant's shoulder-pad does not have to be attached in any way or form to the underface of the shoulders of any of the wearer's garments. Every woman usually wears a brassière; all she has to do is to take the flap or jaw 12, of the shoulder-pad 5, and place same under the brassière shoulder-

strap 18 (brassière not shown) and then snap the fastener 15 into the fastener 16 thereby closing or interlocking the jaws 11 and 12 with each other and bringing same together in a manner whereby they would meet with each other as shown by the dotted lines 19 (see Fig. 2). Thus the shoulder-pad 5 will be held in place in a manner adapted to support the garment shoulder in a raised position. The strap 18 may be provided with openings 21 adapted to receive the stud 22 10 of the snap fastener 15 when interlocking same with the snap fastener 16, thereby preventing the side movements of the shoulder-pad 5, and also holding same locked in desired position.

The shoulder-pad 18 may be provided with a 15 buckle 25 for the purpose of adjusting the strap length to desired sizes, in a manner for example as indicated by arrow A; such buckle in its usual position is located upon the wearer's shoulder and contacts directly the wearer's shoulder-skin. As hereinabove pointed out such a method is highly objectionable to the wearer, causing her discomfort and irritation, in general, presenting a vexing problem commercially. But applicant's invention solves such vexing problem completely; it eliminates entirely the hereinabove mentioned objectionable features. In applicant's structure such buckle 25 is positioned upon the underlying jaw-portion 12 and is kept away from touching the wearer's shoulder-skin, thereby eliminating injuries thereto. Such a method provides comfort and satisfaction to the wearer, and such buckle-pad may prove to be a very desirable wardrobe item, and quite valuable to the trade commercially.

If desired the buckle 25 may be provided with an opening 26, adapted to receive therethrough one of the studs 22 when the latter is engaging the snap fastener 16; thus such buckle may be held safely in desired position.

The same, as hereinabove explained with respect to shoulder-pads, is also true with respect to underarm dress-shields. A dress-shield is usually sewn on to a garment arm hole or pinned on thereto by pins. As pointed out, sewing is not a practical nor a useful method for the average person to resort to, particularly for one who is not skilled in the sewing profession. Neither is it practical, nor advisable, to use pins for the herein purposes, as pins may injure the wearer's under-arm or body, and are therefore objectionable.

The object of applicant's invention is to eliminate the above-mentioned objectionable features, and instead to provide a safe method for the accomplishment of the herein desired purposes. It may therefore be noted, that by utilizing applicant's shoulder-pad as a dress-shield carrier such long-sought-for improved and safe method is hereby being provided.

Applicant's dress shields 28, made in accordance with applicant's invention, is provided with a shoulder-strap 29 which may be positioned upon the underlying jaw-portion 12 (see Fig. 4); such jaw-portion 12 may then be positioned under the shoulder strap 18 and be interlocked with the jaw-portion 11, thus the shoulder-pad 5 may be positioned upon the wearer's shoulder for the purpose of supporting her garment-shoulder and at the same time act as an under-arm dress-shield carrier. The section 28a may be provided with an arm-band 34 adapted to fit around the wearer's arm, so that such section 28a may be positioned against the under-portion of the wearer's arm whereas the other section of the dress 75

shield 28 may be positioned against the wearer's body adjacent to her under-arm, thus eliminating the necessity of sewing or pinning the dress-shield to the armhole of the wearer's garment.

The strap 29 may be provided with openings 31; the edge portions of such openings 31 may be reinforced or covered with suitable means, for example eyelets (not shown). Such openings 31 may be adapted to be anchored by the snap-fasteners 15 and 16, thus holding the dress shield 28 in desired position. It will be understood that the plurality of openings 31 permits the changing or adjustment of the position of the dress-shield (moving same towards the front or rear) with respect to the wearer's under-arm.

If desired, the strap 29 may be secured permanently to the body 5, and such body 5 may then be secured to the shoulder-strap 18, or be removed therefrom whenever desired. Such shoulder-strap 18 does not necessarily have to be that of a brassière; it may be of any other suitable garment, or the under-face of garment-shoulders may be provided with shoulder-straps which may be adapted to have the shoulder-pad anchored thereto. The shoulder-pad 5 may be made in any suitable style or size; it may, if so desired, comprise a padded or thicker under-portion 32 and a flap-section 33 of a lesser thickness than that of the padded or thicker portion 32. The front portion of said flap-section 33 may be separated or flared away from the body portion 32 for the purpose of receiving the shoulder-strap 18, and may then be reverted to normal position and be interlocked with the portion 32 by suitable means, for example, fasteners 15 and 16, in a manner securing the shoulder-pad 5 to the strap 18. By separating the front portion of the flap-section 33 from the portion 32, the shoulder-pad 5 may be easily removed from the shoulder strap 18.

From the above it will be seen that I have invented and perfected a shoulder-pad construction of a new and unique design, a shoulder-pad which is practical, useful and therefore of commercial value, and, although I have shown certain preferred forms of illustrations in order to explain and describe the novelty of my invention, yet, by showing such structures, I do not, by any means, limit myself to the structures, nor to the terms used in describing same, as they are for illustrative purposes only. Various suggestions and changes of structure may be resorted to, and I desire it to be understood that I have same in mind when showing and describing this invention, and seek protection by Letters Patent. And, although I have mentioned in describing this invention of what material certain parts may be made, how they may be formed, shaped or styled and how they may be assembled, yet I desire it to be understood that this structure, or parts thereof, may be made of any suitable material, and shaped, formed, styled or arranged in any desirable manner, and assembled in any convenient way so that the parts may be easily taken apart, removed, cleaned, re-attached, replaced and re-assembled, and that various changes in detail may be resorted to without departing from the spirit of this invention.

I claim:

1. A shoulder-pad comprising a body-portion provided with a plurality of jaw-portions, a spaced section between said jaw-portions, said spaced section adapted to house a strap positioned between said jaw-portions, and means for locking said jaw-portions to each other.

2. A shoulder-pad comprising a body portion provided with a plurality of separable jaw-portions, a spaced section between said jaw-portions, said spaced section adapted to support a strap positioned between said jaw-portions, means for locking said jaw-portions to each other, thereby anchoring said shoulder-pad to said strap, said means adapted to be unlocked from each other thereby removing said shoulder-pad from said strap.

3. A shoulder-pad comprising a body portion provided with a plurality of separable jaw-portions, the inner face of each of said jaw-portions provided with interlocking means adapted to be interlocked with each other thereby closing said jaw-portions, said interlocking means adapted to be unlocked and separated from each other, thereby opening said jaw-portions.

4. A shoulder-pad comprising a body portion provided with a plurality of separable jaw-portions, a spaced section between said jaw-portions, each of said jaw-portions provided with an inner face, each of said inner faces provided with a fastening element, a shoulder-strap adapted to be positioned upon one of said inner faces, the other of said inner faces adapted to be positioned over said strap, the fastening element of one of said inner faces adapted to engage the fastening element of the other of said inner faces, thereby holding said strap in a secured position within said spaced section.

5. A shoulder-pad comprising a body portion provided with a plurality of separable jaw-portions, a spaced section between said jaw-portions, each of said jaw-portions provided with an inner face, each of said inner faces provided with an interlocking element adapted to cooperate with the interlocking element of the other of said faces, said spaced section adapted to support a shoulder-strap therebetween, said shoulder-strap provided with means adapted to engage the said interlocking elements for the purpose of being held in a secure manner in desired position.

6. A shoulder-pad comprising a body portion provided with a plurality of separable jaw-portions, a spaced section between said jaw-portions, each of said jaw-portions provided with an inner face, each of said inner faces provided with snap fasteners, said spaced section adapted to support a shoulder-strap therebetween, said shoulder-strap provided with an opening, the snap fastener of one of said faces provided with a stud adapted to be positioned within said opening and be interlocked with the snap fastener of the other of said faces, thereby closing said jaw-portions and holding said shoulder-pad in desired position, said stud adapted to be unlocked from said snap fastener and be removed from said opening thereby opening said jaw-portions and enabling the removal of said shoulder-pad from said shoulder-strap.

7. A shoulder-pad comprising a body portion provided with a plurality of jaw-portions, a spaced section between said jaw-portions, said spaced section adapted to enclose a portion of a shoulder-strap, one of said jaw-portions adapted to provide cushioning means for said shoulder-strap portion, means for securing said shoulder-pad to said shoulder-strap portion, said shoulder-pad adapted to be removed from said shoulder-strap portion.

8. A shoulder-pad comprising a body portion

provided with a plurality of jaw-portions, a spaced section between said jaw-portions, said spaced section adapted to encase a portion of said shoulder-strap, said shoulder-strap portion provided with a buckle, one of said jaw-portions adapted to provide cushioning means for said shoulder-strap portion and also for said buckle, means for securing said shoulder-pad to said strap portion, said shoulder-pad adapted to be removed from said shoulder-strap.

9. A shoulder-pad comprising a body portion provided with a flap-section, a part of said body portion adapted to be positioned under a shoulder-strap, said flap-section adapted to overlay said shoulder-strap and be secured to said body portion, thereby holding said shoulder-pad in desired position, said shoulder-pad adapted to be removed from said shoulder-strap.

10. A shoulder-pad comprising a body-portion and a flap-section, the rear portion of said flap-section being secured to said body-portion, the front portion of said flap-section adapted to be flared away from said body-portion, said body-portion and said flap-section adapted to support a shoulder-strap therebetween, said front portion provided with fastening means adapted to engage fastening elements located at said body-portion thereby locking said front portion to said body-portion and securing said shoulder-pad to said shoulder-strap.

11. A shoulder-pad comprising a body-portion provided with a flaring element, the free end portion of said flaring element provided with fastening means, said body-portion provided with fastening elements, said flaring element adapted to enclose a shoulder-strap, the fastening means of said flaring element adapted to be interlocked with the fastening elements of said body-portion thereby connecting the free end portion of said flared element to said body-portion and securing said shoulder-pad to said shoulder-strap, said fastening means adapted to be unlocked from said fastening element thereby separating the free end portion of said flared element from said body-portion for the purpose of removing said shoulder-pad from said shoulder-strap.

12. A cushioning shoulder-pad comprising a body-portion and a flap-section, said body-portion and said flap-section adapted to encase a shoulder-strap therebetween in a manner securing said pad to said shoulder-strap, said flap-section adapted to be flared away from said shoulder-strap thereby permitting the removal of said pad from said strap.
